CLAIM

The ornamental design for a fluorescent lamp, as shown and described.

DESCRIPTION

FIG. 1 is a bottom, front and right side perspective view of a fluorescent lamp showing our new design;

FIG. 2 is a front elevational view thereof;

FIG. 3 is a right side elevational view thereof;

FIG. 4 is a rear elevational view thereof;

FIG. 5 is a top plan view thereof; and

FIG. 6 is a bottom plan view thereof;

FIG. 7 is a bottom, front and right side perspective view of a second embodiment of our new design;

FIG. 8 is a front elevational view thereof, the rear being a mirror image;

FIG. 9 is a right side elevational view thereof, the left side being a mirror image;

FIG. 10 is a top plan view thereof; and

FIG. 11 is a bottom plan view thereof.
